UNITED STATES PATENT OFFICE.

JAMES C. SCHLAPPE, OF LOS ANGELES, CALIFORNIA, ASSIGNOR TO HAWTHORNE FURNITURE SHOPS, OF LOS ANGELES, CALIFORNIA, A CORPORATION OF CALIFORNIA.

CONVERTIBLE TABLE TOP.

Application filed April 28, 1925. Serial No. 26,370.

This invention relates to furniture construction, and it relates particularly to a table having a folding top.

It is an object of this invention to provide a library table or the like, which may be readily converted into a dining table or a table having a somewhat larger area than the usual library table.

Another object of my invention is to provide a convertible table of this character in which its convertibleness is not distinguishable. To accomplish this object of my invention I provide a table having a top provided with an ornamental molding extending around the outer edge of the table and extending from the lower face thereof. This construction gives the top the appearance of a library table or other table which is used principally for ornamentation. Leaves are secured to this table in such a manner that their presence is not observed when they are in folded position. These leaves are hinged, however, so that they may be swung outwardly into the same plane as the top of the table, thereby enlarging the area of the top and providing a table which is suitable for dining use.

It is also an object of this invention to provide a table of the character above mentioned in which portions of the leaves of the table serve as parts of the molding when they are in folded position. Where the leaves hinge to the top of the table I divide the molding into two parts, one part I secure to the top and the other part I secure to one of the leaves. These two parts are hinged together so that when a leaf is in folded position, the parts of the molding are disposed so as to form a complete molding entirely around the table.

Other objects and the particular advantages of this invention will be emphasized in the following description.

Referring to the two sheets of drawings which are for illustrative purposes only and in which I illustrate a preferred form of my invention,

Fig. 1 is a perspective view of a table embodying the features of my invention.

Fig. 2 is a bottom plan view of the top of the table shown in Fig. 1.

Fig. 3 is a section taken on the line 3—3 of Fig. 2, this view showing the arrangement for retaining the leaves in retracted or folded position, also showing the man-

ner in which the leaves are retained in unfolded or extended position.

Fig. 4 is an enlarged fragmentary detail taken substantially as indicated by the arrow 4 of Fig. 2, this view showing the leaf in extended position and clearly showing the construction of the molding and the unique manner in which it is divided so that it hides the leaf and still allows it to be swung into an extended position.

Fig. 5 is an enlarged fragmentary perspective view similar to Fig. 4, this view showing a leaf in folded position and clearly showing the manner in which a portion of the leaf comprises the ornamental molding of the table.

In the drawings I show a top 11 which is supported by columns 12 having base formations 13 at the lower end thereof. The table top 11 is preferably rectangular in shape and has the corners cut off so as to provide beveled portions 14. For the purpose of ornamentation and to give the table an esthetic appearance, I provide an ornamental molding 16.

As clearly shown in Figs. 3, 4 and 5, the molding 16 comprises a crown course 17, a dentil course 18 having squared formations 19 and a foot course 20. These courses of the molding are successively receded with respect to each other so as to have a stepped appearance. The crown course 17 and the dentil course 18 extend entirely around the top 11. Sections 23 of the dentil course 18 are made separate from the rest of the course 18 along the sides of the table, and these sections 23 are secured to the crown course 17 by invisible hinges 24 which may be of any standard construction. Secured to the lower faces of the sections 23 are leaves 26. When the leaves are in retracted or folded position, they cooperate with the portions of the molding 16 forming a part thereof and completing the molding entirely around the top 11.

As clearly shown in Fig. 2, the ends 27 of the leaves 26 are extended obliquely with respect to the sides of the table. The edges 29 of the leaves 26 when they are in folded position form a continuation of the foot course 20, thus completing the foot course. Ends 30 of the foot course 20 are beveled and are contracted by ends 31 of the oblique ends 27 of the leaves 26 when these leaves 26 are in folded position.

When the leaves 26 are in extended position, as shown in Figs. 1, 2, 3 and 4, the edges 29 of the leaves 26 engage sides 33 of the top 11, the faces 34 of the leaves 26 at this time being in the plane of the upper face of the top 11. The sections 23 of the dentil course 19 at this time rest in the same plane as the crown course 17. As clearly shown in Figs. 2 and 4, the direction of extension of the oblique ends 27 is such that they align and extend parallel with the beveled corners 14 of the top 11. To provide this accurate alignment and an accurate fitting of the corners 31 with the beveled corners 14, it is necessary to have the leaf extend exactly to the corners 36 at which the sides join with the beveled portions 14. It is not necessary to have the dentil course and the sections 23 separate at this point, and for convenience of manufacture we have extended the course 18 a very short distance along the sides of the top.

Arms 42 of leaf supports 43 extend into a slide 44 secured to the lower face of the top 11 near a central part thereof. Heads 45 are formed at the outer ends of the arms 42. These supporting members 43 may be extended, as shown in Fig. 3, so as to support the leaves 26 in extended position. When the supporting members 43 are in retracted position, the heads 45 thereof form parts of the crown and dentil courses 17 and 18 of the molding 16.

Keepers 50 are secured to lower faces of the leaves 26, these keepers being engaged by pawls 51 which are secured at 52 to the lower face of the table top 11. A releasing plate 54 is hinged at 55 to the table top 11. The releasing plate 54 is adapted to engage arms 56 of the pawls 51 for swinging them out of engagement with the keepers 50, thus unlatching the leaves 26 and allowing them to be swung into extended position. When the releasing plate 54 is operated, both of the pawls are released from engagement with the keepers 50. The leaves, however, may be independently locked in folded or retracted position as the pawls may swing independently of each other.

From the foregoing description and drawing, it will be seen that when the leaves 26 of the table of my invention are in folded

position, the table has the appearance of the usual library table, or the like, and the presence of the leaves or the convertibleness of the table is not evident. This feature is accomplished principally by my novel design of molding which uses a portion of the leaves 26 as a part thereof. This is a very important consideration of my invention as tables of this character are much in demand at the present. There is much use for a table of this character in small apartments where it is necessary to use the parlor for a dining room. The dining table would be much too large and would also detract from the appearance of the room. By use of a table of my invention it is possible to maintain the appearance of the parlor and still have dining table facilities.

I claim as my invention:

1. In a convertible table, the combination of: a top; means for supporting said top; a molding extending around said top; and leaves arranged to swing from retracted into extended position, said leaves when in retracted positions forming a part of said molding.

2. In a convertible table, the combination of: a table top; means for supporting said top; a molding extending around said top, said molding being separated at one portion and forming upper and lower parts; hinges whereby said upper and lower parts are hingedly attached together; and a leaf secured to said lower part of said molding and forming a part thereof.

3. In a convertible table, the combination of: a table top; means for supporting said top; a molding for said top comprising a crown course and a dentil course extending entirely around said top, a part of said dentil course being separate and hinged to said crown course, and a foot course extending part way around said top; and a leaf secured to said separate part of said dentil course, an edge of said leaf completing said foot course when said leaf is in retracted position.

In testimony whereof, I have hereunto set my hand at Los Angeles, California, this 23rd day of April, 1925.

JAMES C. SCHLAPPE.
